UNITED STATES PATENT OFFICE

109,998

DESIGN FOR A COMBINATION DESK UNIT

Alfred E. Detwiler, Lake Worth, Fla.

Application March 10, 1938, Serial No. 75,739

Term of patent 7 years

To all whom it may concern:

Be it known that I, Alfred E. Detwiler, a citizen of the United States, residing at Lake Worth, in the county of Palm Beach and State of Florida, have invented a new, original, and ornamental Design for a Combination Desk Unit, of which the following is a specification, reference being had to the accompanying drawing, forming part thereof.

I claim:—

The ornamental design for a combination desk unit as shown.

ALFRED E. DETWILER.
